UNITED STATES PATENT OFFICE

2,390,728

ORNAMENTING MACHINE

Charles E. Newton, Marlboro, Mass., assignor to
Benjamin W. Freeman, Cincinnati, Ohio

Application May 13, 1940, Serial No. 334,915

13 Claims. (Cl. 101—316)

The present invention relates to shoe machinery, and more particularly to machines adapted to perform during a single cycle of actuation the two operations of cutting shoe upper blanks such as vamps, tips, quarters, foxings, straps, or the like to form ornamental cutouts, edgings, and/or perforations therein or thereon and of applying ink or other marking substance to said blanks in the form of lines which function as guides for subsequent operations such, for example, as the application of ornamental stitching to the blanks or the assembly therewith in proper position of other work pieces for securing by stitching, adhesion, or otherwise.

In connection with the foregoing it should be noted that the cutting operation referred to may include the punching of perforations arranged in a pattern or design, or it may be the cutting out of one or more fairly large openings of ornamental or utilitarian nature, or it may be in the nature of pinking or forming ornamental edges on the work, as is the case of a wing tip or foxing. All of these cutting operations are within the purview of the present invention.

The production of such markings and perforations, edgings, or cutouts was formerly accomplished only by separate operations, the work being marked by hand or by a suitable die in one machine and being perforated or cut by hand or by a suitable die in another machine. Comment need not be made here on the slowness of manual procedure, but even with the use of two machines there were several disadvantages. One of these was the difficulty of getting, for the operation performed second in order, the highly desirable identical work piece gauging used for the first performed operation, and while such gauging was not easy to achieve even with relatively stiff work pieces, it was extremely difficult and sometimes impossible with work pieces made of thin, soft, or light material. A second disadvantage lay in the fact that since two machines necessitated two operations, there was a doubling of apparatus and amount of labor, the latter causing a time stretch-out because the two operations occurred in sequence in contrast to a single operation combining the results of the two.

In the past few years a distinct advance has been made in the art by the introduction of combined marking and cutting machines, i. e., machines so constructed as to perform the two operations of marking and cutting simultaneously or during a single cycle of actuation of a single machine. The advance which such machines have made has been recognized by all shoe manu-

facturers, but these machines are what may be called of a special type, one requiring the purchase of an entire unit, including a press as a part thereof, and such machines are therefore quite expensive.

But as individual marking machines and individual cutting machines are and long have been standard equipment among shoe manufacturers, it will be seen that in addition to the factor of expense of the combined machine, that machine has brought into being a situation such that while the individual machines have been rendered idle for all work done by the combined machine, the utility of the individual machines has not been diminished for their single functions, a very important point since not all work pieces which require marking on the one hand or cutting on the other, require both. The combined machine therefore has not been a complete substitute for the individual machines, and in view of this situation, together with the expense involved, many of the smaller shoe manufacturers have not purchased the special combined machine.

However, the admitted advantages of such combined machines have created a demand for inexpensive single apparatus which performs the two operations of marking and cutting, and as a result constructions have been proposed which may be readily and removably installed in any of the old and well known press machines built merely for various cutting operations, thereby transforming them into combined marking and cutting machines. This type of structure does not involve the expense of acquiring a special entire machine and in addition to this the function of a marking machine is added to that of the already existing and owned cutting machine so that by the installation of inexpensive apparatus shoe manufacturers may have individual or combined machines at will.

The present invention relates specifically to such installed apparatus, and it is the principal object of the present invention to provide inexpensive equipment by which the two operations of cutting and guide line forming may be performed in a single machine during a single cycle of the actuation thereof.

In my copending application, Serial No. 197,447, filed March 22, 1938, one example of such apparatus is disclosed and claimed. It is a further object of the present invention to provide several improvements in the mechanism disclosed in my said application, these improvements relating both to the die structure thereof.

and to the remainder of the apparatus, and to their mode of operation.

To the accomplishment of these objects and of such others as may hereinafter appear, the various features of the present invention reside in certain constructions, combinations, and arrangements of parts, hereinafter fully described and then pointed out in the appended claims, the advantages of which will be readily appreciated by shoe manufacturers and others skilled in the art.

The various features of the present invention will be readily understood by reading this specification with reference to the accompanying drawings, which drawings illustrate the best physical embodiment of the invention at present known to the inventor and in which:

Figure 1 is a view in front elevation of portions of a cutting machine which is provided with apparatus herein disclosed for transforming it into a combined marking and cutting machine;

Fig. 2 is a view in plan of the table, guideway structure, and associated parts, a die structure with portions broken away being shown located on the table;

Fig. 3 is a view in right side elevation of the apparatus, showing the roll carriage in its retracted position and also showing the mechanism for advancing and retracting the die structure along the guideway;

Fig. 4 is a view in right side elevation of the apparatus, showing the roll carriage in its forward position;

Fig. 5 is a view in right side sectional elevation of the apparatus taken along its longitudinal center, the die structure not being shown in section;

Fig. 6 is a view in underside plan of the die structure, portions of the stripper plate being shown broken away;

Fig. 7 is a view in plan of the die structure, the stripper plate being removed;

Fig. 8 is an enlarged detail view in front sectional elevation taken generally along the line 8—8 of Fig. 3;

Fig. 9 is a view in front elevation of the die structure;

Fig. 10 is a view of the die structure in right side sectional elevation, taken along the line 10—10 of Fig. 9;

Fig. 11 is a view of the die structure in right side sectional elevation, taken along the line 11—11 of Fig. 9;

Fig. 12 is a view of the die structure in right side sectional elevation, also taken along the line 11—11 of Fig. 9 but showing the stripper plate somewhat depressed to effect elevation of the marking die;

Fig. 13 is a view of the die structure in right side sectional elevation, taken along the line 13—13 of Fig. 9;

Fig. 14 is a view of the die structure in right side sectional elevation, also taken along the line 13—13 of Fig. 9 but showing the marking die structure elevated by the cams for the reception of marking substance;

Fig. 15 is an enlarged detail view in front elevation, partially in section, of the marking die, showing the mounting of a marking strip in the base portion of the die;

Fig. 16 is a detail view in right side elevation showing a bench mounting for the lever utilized to pull the die structure forward along the guideway;

Fig. 17 is an enlarged detail view in rear eleva-

tion showing associated parts forming the right hand side of the roll carriage; and

Fig. 18 is a detail view in front sectional elevation taken along the line 18—18 of Fig. 5.

For the purpose of disclosure only, the various features of the present invention are herein illustrated as being embodied in the cutting machine disclosed in the patent to Joseph C. Knight, No. 1,584,230, granted May 11, 1926. This well known machine is provided with a bed 25 (Figs. 1, 3-5) and with a slide or plunger 26 which is vertically reciprocable in ways 27 toward and away from the bed and is operatively connected, through the usual treadle-operated, one revolution clutch (not shown) to some suitable source of continuously supplied power such as a flywheel-provided motor. The plunger 26 carries at its bottom face a platen or pressure member 28 having an under facing 29, and a rod 30 mounted in ears 31 at the front of the machine frame 32 functions to guide rearwardly and beneath the facing 29 the usual strip of paper backing 33 (Fig. 5) to prevent cutting of the facing by cutting die elements, as is well understood. The frame 32 rests on a bench 34 (Figs. 1, 16) before which an operator stands, and the bed 25 is provided with a rearwardly extending guide member 35 (Figs. 1-5) medially located between the opposite sides of the bed. Further details of the Knight structure may be found in the above Knight patent and need not be set forth here, but the Knight structure is to be considered for the present invention, as being merely representative of numerous and well known but structurally differing cutting machines, as it will be readily understood that physical embodiments of the present invention may be used in many different press machines and are not confined to use in only the particular machine herein selected for purposes of disclosure. For example, although the illustrated embodiment employs a table corresponding roughly to the anvil structure shown in the above Knight patent, the present invention is applicable to machines which employ neither an anvil nor a table, and is applicable for use with elevated dies and in flat bed machines in which there is no anvil or table nor any elevated die at all; a flat bed die being used.

Adapted to rest upon and be slidable along the bed 25, the illustrated embodiment of the present invention is provided with a table 36 (Figs. 1-5) of the usual integral construction, having a horizontal top, front and rear walls, right and left side walls 37 and 38, respectively, and the usual internal strengthening ribs herein shown as a pair 39 extending between the front and rear table walls and a single rib 40 extending between the side walls 37 and 38. In order that the table 36 may rest upon the bed 25, the front and rear walls of the table and the transverse rib 40 are provided with aligned slots 41 (Figs. 1, 3-5) which receive the bed guide member 35, and with this construction the table 36 may be slid onto the bed to a position for operation in which the table rests beneath the platen 28. Rearward movement of the table may be limited by the abutment of its rear wall with plates 42 secured to and upstanding from the back of the bed, and once the table is thus positioned upon the bed any tendency of forward movement of the former may be prevented by means of bolts 43 (Figs. 2-5) which extend vertically up through the bed 25 at its rear in locations where they may substantially engage the inside face of the rear table wall. While the table 36 is a heavy element, means is preferably provided to insure that it will not tip forward, as will

be hereinafter explained, and to this end the abutment plates 42 are provided with forwardly extending horizontal studs 44 adapted to enter and be received by smooth-walled openings 45, respectively, axially aligned therewith in the rear wall of the table. It will be noted that in the particular table shown the top thereof is wider than the distance between the outside faces of the side walls 37 and 38. Where such a construction is used in an embodiment of the present invention, each of these outside faces and the adjacent portion of the table top preferably merge along a curved surface 46 (Figs. 1-4) to give added strength to the table as a whole.

The table 36 shares in common with anvils, anvil-like structures, and other tables used in cutting machines employing them, or with machine beds themselves when anvils or tables are not employed, the function of supporting beneath the platen 28 a self-contained die structure or assembly 47 (Figs. 1-7, 9-14) herein shown for illustration as being of the flat bed type. But the table is provided with a stationary guideway which functions to position the die structure operatively on the table top, i. e., operatively in the machine, and also functions to slidably receive and support the die structure prior to its operative positioning on the table, i. e., operatively in the machine, and after sliding removal therefrom. In a variant embodiment of the present invention the guideway would be associated with the machine bed itself, for example, as will be understood.

More particularly, the stationary die structure guideway comprises a pair of spaced parallel and vertical plates 48 (Figs. 1-4, 8) and 49 (Figs. 1, 2, 5, 18) aligned with the opposite side portions, respectively, of the top of the table 36 overhanging its side walls 37 and 38. The rear end faces of the plates 48 and 49 are vertical and their upper portions abut the table top while therebelow they abut the vertical front faces of blocks 50 and 51, respectively, bolted and pinned to the table side walls 37 and 38. Rearwardly of the front wall of the table 36 the plates 48 and 49 are provided with parallel and integral extensions 52 and 53, respectively, which rest on the table top and are conveniently secured thereto in proper spaced relation by machine screws 54. In order to maintain the plates 48 and 49 properly spaced at their front ends, aligned openings 55 (Figs. 2-4) are provided therein which receive the opposite reduced end portions 56, respectively, of a transverse rod 57 (Figs. 1-2, 5) the shoulders 58 on which formed by the reduced end portions 56 abut the respective inside faces of the plates 48 and 49. In order to clamp the plates against the shoulders 58, the reduced end portions 56 are each preferably female threaded to receive a bolt 59 the head of which bears against the outer portion of its associated plate.

The plate extensions 52 and 53 cooperate to form a guideway which slidably receives and engages the sides of a die block or base 60 (Figs. 1-7, 9-14) of the die structure or assembly 47 as it rests on the table 36 in an operative position in the machine beneath the platen 28. Forwardly of the table 36 the plates 48 and 49 extend upwardly to a level above that of the plate extensions 52 and 53, and from the level of the plane of the top surface of the table 36 and extending downwardly therefrom the plates 48 and 49 extend inwardly so as to form horizontal rails 61 (Figs. 2-4, 8) and 62 (Figs. 2, 5, 18), respectively, lying in the plane of the top surface of

the table. As the inner vertical faces of the plates 48 and 49 lie in the respective vertical planes of the inner vertical faces of the plate extensions 52 and 53, it will be seen that above the level of the rails 61 and 62 the plates 48 and 49 constitute a forward continuation of the guideway formed by their rearward extensions, while the rails engage the die structure block or base 60 at its lateral bottom face margins to support it from below at the same level that it is supported by the table itself. As a consequence, the plates 48 and 49 function to receive, support, and guide the die structure for sliding movement from a position forward of the table 36 and clear of the platen 28 to and from a position in which the die structure rests on the table and beneath the platen.

Completing the guideway structure above described, the plates 48 and 49 are provided above the level of the rails 61 and 62 with elongated open slots 63 (Figs. 3-4, 8) and 64 (Figs. 5, 18), respectively, the top and bottom walls of which are horizontal and parallel. The slots 63 and 64 each extend from the outer face of their associated plates 48 or 49 to a point short of the inner face thereof, at which points the slots are enlarged to form elongated recesses 65 (Fig. 8) and 66 (Figs. 5, 18) having horizontal and parallel top and bottom walls and a vertical side wall at the opposite sides of the associated slot. As indicated best in Figs. 8 and 18, the bottom wall of each recess is located above the level of its associated rail. The above-described slots and recesses function to receive parts to be described hereinafter, but they are mentioned here for the purpose of completing the description of the physical characteristics of the illustrated guideway.

The die structure or assembly 47 forming a feature of the present invention incorporates both a cutting die element and a marking die element and is of the general character of die illustrated and broadly claimed in my said copending application Serial No. 197,447. The herein illustrated die, however, embodies certain improvements over the die of my said copending application, and while the present die structure is herein shown and described as constructed to operate on a pair of quarters, it is to be understood that this showing is merely for disclosure purposes, as this type of die structure, like that shown in my said copending application, may have its die and gauge elements differently arranged while retaining fundamental constructional and operating features so as to be adapted for forming a wide variety of cutouts, edgings, perforation designs, and guide markings without restriction to use on merely quarters.

Referring to the drawings, the particular die structure 47 shown is provided, in addition to the die block or base 60, with the usual tubes 67 (Figs. 1-3, 5, 7, 9-14) for forming perforations in a work piece, with a tube-holding plate 68 which, with the tubes 67, forms a cutting die, and with a perforated tube rest plate 69. The two plates are secured together and to the base 60 in successive engagement by screws 70 (Figs. 6-7, 9), and are aligned for such securing by pins 71 upstanding from the base, as is customary. Below the holes in the tube rest plate 69 the base 60 is provided with the usual enlarged openings 72 through which punchings may pass downwardly from the tubes 67 and the underlying rest plate holes.

The die structure 47 is also provided with a

stripper plate 73 (Figs. 1-6, 9-14) from which depend posts 74, herein shown as nine in number, which are received, respectively, in a like number of pairs of aligned openings 75 and 76 formed, respectively, in the two plates 68 and 69, and around the posts 74 springs 77 are coiled in interposition between the stripper plate 73 and the top of the base 60. The bottom of the base is provided with recesses 78 (Figs. 6, 10) beneath the pairs of openings 75 and 76, and these recesses form shoulders 79 with the bottoms of passages 80 of less diameter located in the base 60 directly beneath the openings 75 and 76. The passages 80 slidably receive the posts 74, and screws 81 are threaded into the posts so that each screw abuts the associated shoulder 79. The stripper plate 73 is provided with the usual tube holes 82 (Figs. 2, 10-14) and with an open portion 83 (Figs. 2, 10-14) forming a clearance area, and in the illustrated embodiment of the present invention the normal level (Figs. 10-11, 13-14) of the stripper plate 73 is such that its top surface is in the plane of the tops or cutting edges of the tubes 67.

To complete the stripper plate structure, it is provided with a gauge plate 84 (Figs. 1-3, 5, 9-14) having a front wall contoured for registry with corresponding edge portions of a pair of quarters 85, indicated in construction lines in Fig. 2, and there is also provided the usual clip construction 86 for maintaining the work pieces in position on the stripper plate. If desired, the gauge plate 84 may be provided along the top of its front wall with forward projections 87 (Figs. 1-3, 5, 9-10, 13-14), formed by stamping the material of the plate at selected points, and these projections 87 overlie the edgings of work pieces, functioning to prevent any upward displacement of the edgings or to keep them flat if they tend to curl.

By reason of the above construction, the heads of the screws 81 limit the upward movement of the stripper plate 73 to the level stated, while the sliding fit of the posts 74 in the passages 80 and the yielding resistance of the springs 77 permit movement of the stripper plate toward the die block or base 60 under the influence of pressure, as provided by the downward stroke of the plunger 26. As a consequence, and as is well understood, when any work piece is mounted on the stripper plate 73 and the die structure is on the table 36, descent of the plunger presses the stripper plate and the work piece downward to perforate the latter by means of the tubes 67, after which, upon the rise of the plunger, the springs 77, previously compressed on the downward stroke of the plunger, force the stripper plate up to its normal position and in so doing effect the stripping of the work piece from the tubes 67.

In order to provide for marking guide lines on a work piece during the cutting operation, the present invention contemplates the association with the above-described structure of a marking die and actuating elements therefor. To this end, and with reference to Figs. 1-3, 5, 7, and 9-15, the illustrated embodiment of the present invention is provided with a plate 88 having upstanding therefrom edgewise as separate pieces strips 89 the tops of which taper to form marking edges 90 lying in a plane. Between and adjacent the strips 89 the plate 88 is provided with openings 91 (Figs. 7, 10-14) through which the tubes 67 freely extend, and for disclosure purposes the strips 89 are shown curved and bent into conformity to the design or arrangement formed by the tubes 67. The plate 88 is narrower (Fig. 7)

than the tube plate 68 so as to avoid its four front and four rear openings 75, but has an overall size larger than that of the clearance opening 83 in the stripper plate so that portions of the plate 88 extend between the stripper plate and the die block 60, i. e., so that portions of the stripper plate are superposed over the plate 88. In order to accommodate the stripper plate post 74 and its spring 77 which are within the area of the plate 88, the last named is provided with an opening 92 (Fig. 7) aligned with the associated openings 75 and 76 therebeneath.

The plate 88 normally rests on the tube plate 68 as shown in Figs. 1, 9-11, and 13, but as will be hereinafter described, the plate 88 is mounted for movement vertically away from and back to this normal position of rest. In order to guide the plate 88 in its vertical movement, the plate is provided with openings 93 (Figs. 2, 7, 13-14) each of which receives the upper split end of a vertically depending post 94 (Figs. 2, 6-7, 9, 13-14), the posts being slidable in guide passages 95 (Figs. 9, 13-14) formed by aligned openings extending through the tube plate 68, the tube rest plate 69, and the base 60. As shown in Figs. 9-11 and 13, the strips 89 have such height that when the plate 88 rests on the tube plate 68, the plane of the marking edges 90 is lower than that of the tops or cutting edges of the tubes 67. Specifically, the plane of the marking edges 90 is herein illustrated only for disclosure purposes as being slightly below the level of the bottom surface of the stripper plate 73.

In order to join the strips 89 to the base formed by the plate 88, resort may, of course, be had to solder. It is preferred, however, to provide the plate 88 with rows of holes 96 (Figs. 10, 15) which may or may not be circular, each row conforming to the curve and/or bend which a strip 89 is to have, and then to form teeth or projections 97 (best seen in Fig. 15), as by sawing, punching, or milling, along the bottom of the strip, thereafter forcing the teeth into the holes 96 to secure them there frictionally and smoothing off any burrs or portions of the teeth which may extend below the level of the bottom of the plate. The top portions of the strips 89 may be tapered to form the marking edges 90 either before or after the teeth 97 are forced into the holes 96, but tapering after forcing is preferred since it will be found convenient to tap the top edges of the strips to start the teeth in the holes and then to turn the plate 88 upside down with the strips resting on some suitable uniformly yielding material, thereupon tapping or otherwise exerting pressure against the plate until the teeth 97 are forced home. The marking edges 90 may be continuous, as shown, or may each comprise spaced portions to provide broken lines. It will be appreciated, of course, that it is entirely within the scope of the present invention to have the strips 89 and the plate 88 integral, as is the marking die shown in my said copending application, but since strip material and plate material are readily purchased as such, it will be seen that the above-described construction is more easily manufactured than is integral type which requires considerable milling and machining of an originally thick plate to form a thin plate from which integral and accurately edged ribs or strip-like portions upwardly extend to provide marking edges.

The present invention contemplates that in the use of the above-described die structure the marking die formed by the plate or base portion 88

and the strips 89 shall be elevated from its Figs. 1, 9-11, and 13 or normal retracted position of rest on the tube plate 68 in two different manners and for two different purposes, one for the application of marking substance, preferably a suitable ink, to the marking edges 90 since such application is not practicable when the marking edges are located below the tops or cutting edges of the tubes 67, and the other for moving the inked marking edges 90 into marking engagement with work pieces engaged with the stripper plate 73.

To achieve elevation of the marking die for the latter of the above two purposes, the present invention contemplates that the assembly 47 be provided with means forming a part thereof and actuatable to raise the plate 88, attention here being called to the fact that for this purpose there is herein disclosed a lever construction which, while retaining the functions of that disclosed in my said copending application, is much simpler and sturdier and is more easily made. To this end the top of the die block or base 60 is preferably, although not necessarily, provided with elongated recesses 98 (Figs. 7, 9-14) of identical construction, comprising a spaced pair located parallel to and adjacent the rear edge of the base and a spaced pair similarly located with respect to the front edge of the base. Each recess 98 has parallel long sides and rounded ends, and the tube rest plate 69 is provided with openings 99 which have the same shape as the recesses 98 and overlie them, respectively, as the tube rest plate is supported on the base 60. The aligned recesses 98 and openings 99 form sockets for the reception of rocker-pins 100, each of which has projections 101 of reduced diameter extending from its opposite ends for location in the rounded ends of the sockets. As shown best in Figs. 11 and 12, the tops of the projections 101 lie slightly below the level of the top surface of the tube rest plate 69, and to hold the rocker-pins 100 in their sockets while permitting them to rock freely, the cutting die base formed by the tube plate 68 is provided with elongated notches 102 (Figs. 7, 9, 11-12), the short ends of which overlie (Fig. 7) the rounded ends of the sockets and hence overlie the rocker-pin projections 101. Extending inwardly from the long sides of the notches 102 the upper portion of the tube plate 68 is provided with elongated recesses 103 (Figs. 7, 9-14) the inner portions of which underlie the plate 88, and received flatwise in the recesses 103 are the inner portions of levers 104 (Figs. 1-2, 6-7, 9-14) which are preferably not thicker than the depth of the recesses 103, and may be thinner, so that the lever inner portions underlie the plate 88 as it is supported by the tube plate 68. The levers 104 are made of resilient strip spring material, extend outwardly beyond the front and rear edges, respectively, of the base 60, are preferably, although not necessarily, of equal length, and at points between their ends are secured, as by rivets 105 (Figs. 7, 9-14), to flat surface portions 106 on the rocker-pins 100, these surface portions lying substantially in the plane of the bottoms of the tube plate recesses when the rocker-pins are in their normal or Fig. 11 position. Completing the die structure mechanism actuatable to effect elevation of the marking die for work marking purposes, the stripper plate 73 is provided with depending front posts 107 (Figs. 1-3, 5-6, 9-14) and rear posts 108 overlying the outer ends of the associated levers 104.

With the above arrangements, it will be seen that the tube plate 68 serves to hold the levers

104 swingably secured in the die structure 47 by reason of portions of the tube plate overlying the rocker-pin projections 101. It will also be seen that when the stripper plate 73 and the work supported thereby descend, as under the influence of the plunger 26, the posts 107 and 108 press against the levers 104, thereby swinging their outer portions downward and simultaneously causing their inner portions to swing upward, and 10 that since the inner portions of the levers 104 underlie the plate 88, this swinging movement necessarily causes the inner ends of the levers to push the plate 88 and the strips 89 upward so that the marking edges 90 engage the work and mark it. Since the presence of the gauge plate 84 on the stripper plate 73 causes the portion thereof to which it is attached to flex downwardly (Fig. 12) under the influence of the plunger 26 before the remainder of the stripper plate descends, as 15 is well known, the rear posts 108 are shorter than the front posts 107 so that the inner ends of all the levers 104 will engage and exert upward pressure on the plate 88 simultaneously. In the particular die structure shown in the drawings the levers 104 have identical power, fulcrum, and 20 work point locations. Should it be desirable, however, to vary any one or all of these three factors for a given die structure, or to vary the length of one or more of the levers 104 at either 25 or both sides of the fulcrum thereof, or to vary the thickness of the gauge plate 84, it will be understood that the length differential between the posts 107 and 108 and also the location of the posts may be varied as required by these changed 30 conditions to effect the simultaneity of engagement of the inner ends of the levers 104 with the plate 88.

In order to elevate the marking die so that the marking edges 90 are in a position to receive ink or other marking substance to the exclusion of the tops or cutting edges of the tubes 67, i. e., in order to elevate the marking edges 90 above the plane of the top of the gauge plate 84 and hence above the tops or cutting edges of the tubes 67, 40 a different elevating arrangement in the die structure than that above described is contemplated. More particularly, use is made for this purpose of the posts 94 which depend from the plate 88 and are received in the passages 95 45 which guide the vertical movements of the posts and hence that of the plate.

Referring to Figs. 6, 9, 13, and 14, the lower ends of the pairs of posts 94 at each side of the plate 88 are secured to horizontal bars 109 which 50 are freely received in slots 110 formed in the bottom of the base 60 of the die structure in parallelism with the sides thereof. The depth of the slots 110 is preferably greater than the height of the bars 109, and to give even more space 55 above the latter, the slots 110 communicate upwardly with recesses 111 formed in the base above the bars 109 and being slightly larger than the bars so as to be capable of freely receiving them when they are pushed upward, as will be 60 described. As shown in Fig. 13, the length of the posts 94 is such that when the plate 88 rests on the tube plate 68, the bottoms of the bars 109 do not extend below the level of the bottom of the base 60. But it will be appreciated by 65 comparing Figs. 13 and 14 that when the bars 109 are pushed upward, the marking edges 90 may be elevated, by reason of the elevation of the plate 88 and the posts 94, above the level of the tops or cutting edges of the tubes 67 and 70 also above the plane of the top surface of the

gauge plate 84, this result being possible because the distance between the tops of the bars 109 and of the recesses 111 is greater than the distance between the plane of the top surface of the gauge plate 84 and the plane of the marking edges 90 as the plate 88 rests on the tube plate 68.

In order to elevate the bars 109 and so elevate the marking die to place the marking edges 90 in the advanced position just described, the present invention contemplates that this result be achieved by mechanism which is positively actuatable while the die structure is supported on the rails 61 and 62 in advance of the machine bed 25, i. e., in advance of the table 36. But the present invention also contemplates that this mechanism shall be actuatable for this purpose by operative connection with the mechanism for depositing marking substance on the marking edges 90, and in view of this compound structure and mode of operation, it is deemed best to proceed first with a description of the bar-elevating mechanism, then with a description of the depositing mechanism, and then with a description of the operative connection between the two.

Accordingly, the guideway plates 48 and 49 are provided below the level of the rails 61 and 62 with aligned openings which receive the opposite ends of a cam shaft 112 (Figs. 1-5) the outer portions of which extend beyond the outer surfaces of the plates, as shown best in Figs. 1 and 2. Between the plates 48 and 49 the cam shaft 112 carries two cams 113 of identical construction, each comprising a body portion secured to the shaft by a set screw 114 extending into a passage (Fig. 5) formed in the shaft and a peripheral portion of reduced width having an arcuate cam surface 115 of about 180°. The cams 113 are aligned along the shaft 112 and are spaced apart so as to have their cam surfaces 115 located, respectively, in the vertical planes (Fig. 1) of the slots 110 in the bottom of the die base 60, i. e., of the bars 109 depending therein. The cams 113 are normally in a deactuated condition, i. e., located entirely below the level of the rails 61 and 62 (Figs. 1, 3, 5), but the radius of the cam surfaces 115 is such that when the cam shaft 112 is rotated to actuate the cams, as will be described, the cam surfaces extend (Fig. 4) above the level of the rails 61 and 62, i. e., above the level of the bottom of the die base 60, so that they may engage and push up the bars 109 and so elevate the marking die. Specifically, the radius of the cam surfaces 115 is such that when they engage the bottoms of the bars 109 and push the bars up into the recesses 111, the plate 88 is elevated (Fig. 14) so that the marking edges 90 are above the plane of the tops or cutting edges of the tubes 67 and also above the plane of the upper surface of the gauge plate 84. The tops of the bars 109 preferably do not engage the tops of the recesses 111, and the upper surface of the plate 88 preferably does not engage the under surface of the stripper plate 73, when the bars are elevated by the cams 113 as shown in Fig. 14, this arrangement being provided so that there is no danger of the cams lifting or tilting the die structure as a whole with respect to the rails 61 and 62 and so as to allow maximum tolerance in selecting the radius for the cam surfaces 115.

As indicated in Fig. 4, the cams 113 are operative to elevate the bars 109 when the die structure 47 is moved to a proper position forward

on the rails 61 and 62 ahead of the machine bed 25, i. e., ahead of the table 36. To insure that this forward movement of the die structure will not be too great, i. e., to insure that the die structure will be in such location that the bars 109 will overlie the cams 113 so that the latter may perform their elevating function, the plates 48 and 49 are provided with aligned stops each of which comprises a plate 116 (Figs. 1-5, 18) secured to the inner face of its associated plate 48 or 49 by a bolt 117. The stop plates 116 extend above the level of the rails 61 and 62, i. e., above the level of the bottom of the base 60 and in the path of movement thereof, and to insure that the stop plates do not turn on the bolts 117, the top of each plate may be provided with an outward lip 118 which rests on the associated rail 61 or 62 and preferably is spaced from the adjacent plate wall thereabove, as shown best in Fig. 18.

In order to deposit marking substance on the marking edges 90 when elevated by the cams 113, a pad may be brought into engagement with the edges to ink them or the edges may be manually provided with marking substance in any other manner, but the present invention contemplates that preferably a reciprocable carriage be provided for holding a roll to deposit marking substance on the marking edges by rolling contact therewith. To this end, and referring to Figs. 5, 8, and 18, the slots 63 and 64 formed in the guideway plates 48 and 49, respectively, each receive a horizontal block 119 which slidably engages the top and bottom walls of its associated plate slot. The slide blocks 119 each extend inwardly from the outer faces of the plates 48 and 49 to the inner faces thereof above the level of the rails 61 and 62, and extending from the vertical side walls of the plate recesses 65 and 66 inwardly to said inner plate faces the opposite end portions of each slide block 119 are provided with upper and lower integral lips 120 which slidably engage the top and bottom recess walls and slidably abut the vertical side walls thereof to prevent movement of the blocks 119 outwardly through the slots 63 and 64. Connected as by machine screws and pins to the outer faces of the slide blocks 119 and slidably engaging the outer faces of the plates 48 and 49, respectively, are the lower end portions of upstanding plates 121 (Figs. 1, 3-4, 8, 17) and 122 (Figs. 1, 5), and at their upper ends these plates are connected front and rear by transverse rods 123 (Figs. 1-5, 17) which extend across the apparatus and at their opposite ends have slots into which the plates 121 and 122 fit for attachment by screws. With this arrangement it will be seen that a carriage is formed which is reciprocable horizontally along the guideway plates 48 and 49 by reason of the sliding fit of the slide blocks 119 in the slots 63 and 64, which is of rigid construction by reason of the connections of the plates 121 and 122 both to the slide blocks 119 and to the rods 123, and which is movably secured in the apparatus by reason of the abutment of the block lips 120 with the vertical side walls of the recesses 65 and 66.

Above the level of the tops of the guideway plates 48 and 49 the plates 121 and 122 are each provided with spaced front and rear ways 124 (Figs. 3-5, 8) and 125 which receive front and rear slide blocks 126 and 127, respectively, each having lips extending from the opposite sides of their inner and outer faces so that the slide blocks can move only vertically in the ways. Each slide block 126 and 127 is supported upon a pin 128

which extends upwardly from the top of a passage 129 (Fig. 8) formed one in the bottom of each of the ways 124 and 125, and within the passages the pins are of greater diameter to form shoulders 130 and are hollowed out to receive the upper ends of upstanding helical springs 131 the lower ends of which rest on the bottoms of the passages 129. Ferrules 132 threaded in the upper portions of the passages 129 serve as abutments for the pin shoulders 130 and hence permit downward movement of the pins 128 against the yielding resistance of the springs 131 while preventing the escape of the pins from the passages. The plates 121 and 122 are cut away at their upper rear ends to pivotally receive, as by a bolt 133, ears 134 (Fig. 17) and 135 (Fig. 5) formed at the back of hinge plates 136 and 137, respectively, which overlie the tops of the plates 121 and 122 and may be secured at the forward ends thereof by knurled headed screws 138, and in order to maintain the slide blocks 126 and 127 pressed against the pins 128, the hinge plates 136 and 137 are each provided with a pair of front and rear knurled headed screws 139 (Figs. 2-5, 8) and 140 which extend downwardly into engagement with the respective slide blocks 126 and 127 and are held in a position of adjustment by lock nuts 141.

Journalized in the front slide blocks 126 are the reduced end portions of a shaft 142 (Figs. 1-2, 5, 8, 17) provided with collars 143 between which the shaft is of greater diameter and may be provided with longitudinal ribs 144 (Fig. 5) which serve to hold against rotation with respect to the shaft a preferably sponge rubber cover of cylindrical exterior and substantial thickness so as to form a marking substance applying roll 145. Journalized in the rear slide blocks 127, and at a level somewhat higher than that of the shaft 142, are the reduced end portions of a shaft 146 (Figs. 2, 5, 17) which is parallel with the shaft 142 and has a preferably smooth rubber cover so as to form a roll 147. With reference to Fig. 5 it will be seen that the roll 147 exerts a slight pressure on the roll 145, thereby being rotatable by the rotation thereof, and functions not only to spread along the roll 145 marking substance applied thereto in any suitable manner but also to squeeze the roll 145 to bring to its surface marking substance caught in its voids. Since the function of the roll 145 is to deposit marking substance on the marking edges 90, and since the marking edges are intended to receive marking substance when the bars 109 are elevated by the cams 113, it will be seen that the lowermost element of the periphery of the roll 145 should preferably be located slightly below the plane of the thus elevated marking edges 90 and of course not above it. This is achieved by turning the adjusting screws 139 to move the front slide blocks 126 and therefore the roll 145 to the proper level, after which the adjusting screws 140 are turned to move the rear slide blocks 127 and therefore the spreader roll 147 to the proper level so that the latter engages the roll 145 as stated above.

To facilitate pulling the roll carriage forward to cause the deposition of marking substance on the marking edges 90, the above-described carriage construction may be provided with a handle 148 (Figs. 1-5). The opposite ends of the handle 70 are provided with pins 149 which are received in upstanding ears carried by arms 150 located one at each end of the handle and having their opposite ends provided with bosses 151 the outer ends of which terminate adjacent the plates 121 and 75

122 and receive the front and rear rods 123 so as to be supported thereby.

In order to provide an operative connection between the roll carriage or marking substance applying mechanism and the cams 113, the present invention contemplates the employment of mechanism of such nature that a pulling forward of the carriage manually, as by the handle 148, automatically effects rotation of the cam shaft 112 and the cams 113 thereon and thus effects elevation of the marking edges 90 to a position to receive marking substances. But the present invention also contemplates that preferably means be provided which automatically returns the roll carriage and effects lowering of the marking edges so that the carriage need not be pushed back manually, this construction and mode of operation being desirable, although not necessary, because of the speedier use of the apparatus resulting therefrom.

Referring to Figs. 1-5 and 8, the illustrated embodiment of the present invention is provided with a pair of L-shaped, upstanding plates 152 and 153 of identical construction. The short bottom legs of these plates extend rearwardly in engagement with the outer faces of the blocks 50 and 51, respectively, and are secured thereto by machine screws 154, while the upstanding portions of the plates 152 and 153 engage flatwise the outer faces of the guideway plates 48 and 49, respectively, and are secured thereto by machine screws 155. This type of securement serves not only to hold the plates 152 and 153 securely in position but also to maintain parallel the portions of the plates 48 and 49 just ahead of the table 36. The front faces of the plates 152 and 153 are aligned with the rear faces of the plates 121 and 122, respectively, and thus form stops for limiting their movement and that of the roll carriage as a whole. Associated with the plates 152 and 153 are elements of corresponding construction for each plate but located as groups at their opposite outer sides of the plates 48 and 49, and since these elements are corresponding for each side a description of those at the outer side of the plate 48, for example, will serve as a description of those at the outer side of the plate 49.

The L-shaped plate 152 secured to the block 50 and the guideway plate 48 receives the split shank of a bolt 156 the head of which extends outwardly from the inner face of the plate 48 in which it is mounted, and the shank of the bolt 156 extends outwardly beyond the outer face of the plate 48 and from that point receives, in outward order, a circular, spring-retaining plate 157, a cup 158 the open end of which engages the plate 157, the lower end of an upwardly and forwardly extending lever 159 secured by rivets 160 to the closed or outer end of the cup 158, and two nuts 161 which function to maintain the foregoing elements mounted on the bolt 156. The cup receives a spiral spring 162 the outer end of which (Figs. 1-4, 8) extends outside the cup 158 through a slot in the wall thereof and is bent into engagement with said wall, while the inner end of the spring 162 is located within the cup in the slot 163 formed by the splitting of the shank of the bolt 156. The spring 162 is partially wound or stored with power as the lever 159 is in its normally retracted or Fig. 3 position so as to effect a rearward push on the lever, and the direction of convolution of the spring 162 is such that it becomes further wound and stored with power as the lever 159 is swung forwardly, or to the left, viewing Fig. 4.

Pivots connected to the upper end of the lever 159 is the upper end of a link 164 (Figs. 1-5, 8) which extends downwardly and forwardly and has its lower end pivotally mounted on the smooth shank of a stud 165 threaded into the carriage plate 121, a washer 166 being interposed between the link 164 and the head of the stud. Behind the link 164 the stud shank receives the rear end of a second link 167, and between this link end and the carriage plate 121 the stud 165 carries a spacing collar 168 (Figs. 1-2, 8). Disregarding for a moment the end of the second link 167 and bearing in mind that the plate 153 secured to the block 51 and the plate 49 is also provided with a split bolt 156 and parts corresponding to those above described, it will be seen that by reason of the springs 162 and the connection between the levers 159 and the studs 165 afforded by the links 164, the plates 121 and 122 (and therefore the roll carriage) are normally in a rearward or retracted position in which they engage the front faces of the plates 152 and 153, respectively, and that when the roll carriage is pulled forwardly along the guideway plates 48 and 49, the upper portions of the levers 159 are swung forwardly so that the springs 162 are stored with more power than they normally have, which additional power is released when the carriage is released so that the springs automatically pull the carriage back until the rear faces of the plates 121 and 122 again engage the plates 152 and 153.

Referring again to the second link 167, its forward end is pivotally connected to the upper end of a second lever 169 (Figs. 1-5), and this lever is loosely fulcrumed at an opening 170 therein (Figs. 3-4) which receives the end portion of the cam shaft 112 projecting outwardly from the plate 48. At its lower end the lever 169 is pivotally connected by a stud 171 to the lower end of an arm 172 (Figs. 1-5) the upper end of which is bossed to receive the projecting end of the cam shaft 112. The shaft is provided with an opening for the reception of a set screw 173 carried by the boss, and the foregoing construction is completed by a spacing collar 174 (Figs. 1-2) mounted on the stud 171 and interposed between the lever 169 and the arm 172.

In view of the foregoing, and again bearing in mind that the elements just described have their counterpart at the outer side of the guideway plate 48, it will be seen that when the roll carriage is pulled forward, the studs 165 push forwardly on the links 167 which thereupon swing the levers 169 on the cam shaft 112 and hence effect its rotation by reason of the arms 172 being fast on the cam shaft 112 and pivotally connected to the levers 169. As a result the cams 113 are turned or actuated to bring their cam surfaces 115 above the plane of the rails 61 and 62, i. e., above the level of the bottom of the bars 109 as the die structure engages the stop plates 116, and so effect the desired elevation of the marking edges 90 to a location for the reception of marking substance from the roll 145. The cams 113 begin to rotate as soon as forward movement of the roll carriage is initiated, and for this reason the cams are so located on the cam shaft 112 that the cam surfaces 115 engage and push up the bars 109 before the roll 145 reaches the rearmost marking edges 90, and by giving the cam surfaces an extent of some 180°, maintenance of the cam surfaces in engagement with the bars 109 is assured so that the forwardly moving roll 145 passes over all the

marking edges 90 in rolling contact therewith. By the same token it will be seen that when the handle 148 is thereafter released, so that the springs 162 retract the roll carriage and cause rotation of the cams 113 in the opposite direction, the cam surfaces 115 will not leave the bars 109 until the roll 145 has moved rearwardly beyond the rearmost marking edge.

Consideration of the entire structure thus far set forth will show that an operative organization has been provided by which the marking edges 90 may receive marking substance for transfer to a work piece. The above-described table and guideway structure may be installed in a cutting machine as a unit, thereby making it a combined marking and cutting machine. The die assembly 47 is a self-contained structure and may be provided with the usual handle (not shown) and be located in the apparatus with the die block or base 60 on the rails 61 and 62 and engaged with the stop plates 116, and assuming that the roll 145 is properly supplied with ink or other marking substance, an operator can pull the roll carriage forward, as by the handle 148, whereupon the cams 113 will effect elevation of the marking edges 90 and the forwardly moving roll 145 will engage them by rolling contact and deposit marking substance on them. Upon release of the carriage handle 148 the springs 162 will effect rearward movement of the carriage, the roll 145 thereupon passing over the elevated marking edges a second time and the cams 113 then being deactivated, i. e., rotated out of engagement with the bars 109. As the bars then drop by gravity and with them the plate 88, the marking edges 90 will assume their normal position below the level of the tops or cutting edges of the tubes 67, and while the die structure remains on the rails 61 and 62 the operator may secure work pieces on the stripper plate 73 in proper position, then push the die structure along the rails rearwardly and onto the table 36, i. e., into operative position in the machine, beneath the platen 28, and thereupon effect both cutting and marking of the work by depressing the pedal (not shown) forming part of the cutting machine and connected to its clutch. The cycle of operation is completed by the operator pulling the die structure forward by its handle and into engagement with the stop plates 116, whereupon removal of the marked and cut work leaves the apparatus in condition for use in the above-described manner with further work pieces.

But while the above mode of operation is entirely possible and practicable, it is not as fast as may otherwise be the case, and in addition to this, it will be appreciated that since the roll 145 engages the elevated marking edges 90 both when the roll moves forwardly and when it moves rearwardly, unless the operator forcibly holds the die structure, as by its usual handle (not shown), against the stop plates 116 when the roll carriage is released, the roll 145 might pull the whole die structure with it during this rearward movement, thus not only drawing it away from the cams 113 and hence making it impossible during this rearward movement to place further marking substance on the marking edges to insure that all will have a proper amount but also requiring the operator to pull the die structure forward again to a convenient position for placing work pieces upon it.

In order to avoid displacement of the die structure 47 by the roll 145 during the rearward move-

ment of the roll carriage, and to provide for speedier operation than that set forth above, the present invention contemplates that means be provided by which an operator, without using his hands, can draw a die structure out of operative positioning in the machine and into engagement with the stop plates 116 and can hold the die structure there during both forward and rearward movement of the roll 145 in engagement with the marking edges 90. The present invention also contemplates in this connection that means be provided which automatically returns the die structure to its operative position in the machine, thereby rendering it unnecessary for an operator to push the die structure there with his hands after he has mounted work pieces on it.

To these ends the die block or base 60 of the die structure is provided at its front center with a forwardly extending screw having an eye 175 (Figs. 1-2, 5-7, 9-14) and functioning to support a stop member 176 the lower portion of which extends downwardly below the level of the bottom of the die base 60. Releasably clipped to the eye 175 is one end of a cord 177 (Figs. 1-5) which extends forwardly for reception in the groove of a sheave 178 rotatably received on the rod 57 at the front portion of the guideway plates 48 and 49. As shown in Fig. 5, the rod 57 is provided with a peripheral groove 179 for receiving a set screw 180 carried by the sheave 178, and with this construction the sheave is maintained centrally located on the rod 57 in alignment with the eye 175. Below the sheave 178 the cord 177 extends to a point of attachment at the front end of a lever 181 (Figs. 1-3, 5) the rear end of which is pivotally mounted on a pin 182 carried by the ears of a bracket 183 mounted on the front of the machine bed 25. Adjacent the bracket 183 the lever 181 is provided with openings 184 by any one of which the upper end of a link 185 may be pivotally secured to the lever 181, and the link 185 extends downwardly and forwardly and at its lower end is pivotally connected to a lever 186 (Figs. 2-3). In turn the rear end of the lever 186 is pivotally connected to a bracket 187 suitably secured to the floor 188, and the front end of the lever 186 is provided with a pedal 189. Completing this structural arrangement, the die block 60 is provided at its rear with spaced screws having eyes 190 (Figs. 3, 5-7, 10-14) to each of which is releasably clipped a cord 191 (Figs. 1-5), and the cords extend rearwardly over sheaves 192 pivotally mounted in alignment with the eyes 190 upon brackets 193 secured to the rear wall of the table 36. The lower ends of the cords 191 are attached to a depending weight 194 which is heavier than the die structure 47 and is sufficiently heavy to overcome the pull of gravity on the levers 181 and 186 and the link 185 so that the pedal 189 is normally raised as shown in Fig. 3.

With the foregoing structural features, the weight 194 yieldingly tends to maintain the die structure 47 normally located on the table 36, and the stop member 176 limits the rearward movement of the die structure so that the weight does not pull it off the rear of the table. Furthermore, by reason of the above-described operative connection between the die structure and the pedal 189, it will be seen that depression of the pedal effects forward movement of the die structure into engagement with the stop plates 116, the hands of the operator remaining free. Moreover, since the pedal 189 is easily maintained depressed by the foot as long as desired—the

length of the cord 177 preferably being such that the pedal substantially engages the floor 188 when the die structure base engages the stop plates 116—maintenance of the foot on the pedal 5 when the roll carriage is released prevents the engagement of the roll 145 with the elevated marking edges 90 from resulting in the drawing of the die structure 47 rearwardly along the rails 61 and 62 and hence away from the cams 113. As 10 a final point, release of the pedal 189, after the marking edges 90 have been provided with marking substance and have been lowered to their normal retracted position and after work pieces have been secured on the stripper plate 73, permits the weight 194 to descend and so draw the die structure along the rails and into its operative position in the machine as determined by the stop member 176. It will be appreciated that since the lever 181 is a lever of the third class, the nearness to its fulcrum 182 of the upper end of the link 185 results in a relatively short downward stroke of the pedal 189 producing a relatively long downward swing of the front end of the lever 181, and with this arrangement the pedal need not move through an arc commensurate with the distance between the front of the table 36 and the rear or abutment faces of the stop plates 116.

While the above-described structure provides that the lever 181 is pivotally secured to the bed 30 25 of the machine, it is not necessary that this mounting location be selected, and where a press machine is used the bed of which is not adapted to receive the bracket 183 or its equivalent or where it is not convenient or desired to tap the machine itself for reception of such a bracket, the lever 181 may be pivotally mounted on the bench 34 below the machine frame, a support 195 (Fig. 16) being bolted to the front of the bench as a mounting for a bracket 196 the ears of which 35 40 pivotally receive the rear end of the lever 181 for this purpose. The operative connection of the lever 181 with the pedal 189 will not be changed in principle with such an arrangement, as it will be appreciated that although the bench 34 is below the bed, the lever 181 will preferably be upwardly and forwardly tilted (Fig. 16) so that its front end will have a sufficiently long swing. It may be pointed out also that in either of the above arrangements for operatively connecting the levers 181 and 186 it is not essential that the link 185 be made of stiff material, for a cord will function as well.

It has been brought out above that when the plunger 26 descends, it presses the work pieces and the stripper plate 73 downward, thereby causing the tubes 67 to pierce and cut the work. It has also been brought out above that as the stripper plate descends, the posts 107 and 108 depending therefrom press down the outer portions of the levers 104, thereby causing their inner portions to swing upward and so elevate the plate 88 from its normal retracted position, with the result that the marking edges 90 engage work pieces that are descending. In view of the two facts that the work pieces are supported by the upper surface of the stripper plate, which upper surface is normally substantially in the plane of the tops or cutting edges of the tubes 67 and above the plane of the marking edges 90, and that the marking edges rise into engagement with work pieces that are descending, it will be seen that the initial engagement plane of the work pieces and the marking edges 90 is somewhat lower than that of the tops of the tubes and somewhat higher than that of the normal retracted level of the

marking edges. As a consequence, the effect of the pressure of the plunger 26 on the stripper plate 73 to effect engagement of the work pieces and the marking edges is to cause the latter to approach the plane of the tops of the tubes 67, i. e., to cause a decrease in the normal spacing between the plane of the tops of the tubes and the plane of the marking edges. The marking edges thus do not actually reach the level of the tops of the tubes because the descending work pieces have already passed that level and have been at least partially pierced by the tubes by the time marking engagement with the marking edges occurs.

It will be understood that this same result will occur if cutout or edge cutting elements are employed with or in place of tubes, and it will also be seen that as a result of this partial piercing of the work pieces prior to their being marked the present invention, like that of my said copending application, does not rely, for the maintenance of the work pieces over the stripper plate clearance opening 83 in proper position for marking, merely upon the customary squeezing action resulting from the work pieces being between a resiliently mounted stripper plate and a pressure surface or platen. Supplementing this squeezing action, which can exist only outside the clearance opening 83 so far as the stripper plate is concerned, is the impalement by the tubes 67 of the portions of the work pieces overlying the opening 83, and since the tubes are located adjacent the strips 89, as shown in Figs. 2 and 7, the portions of the work pieces overlying the opening 83, in being impalingly pressed onto the tubes before marking can occur, are held by the tubes from any creeping with respect to the marking edges 90. There is thus no danger of the marked lines being blurred or thick as a result of creeping of the work.

The above approach of the marking edges 90 to the plane of the tops of the tubes 67 takes place shortly after the work pieces and the stripper plate 73 begin to move toward the die block 60 and impalement of the work pieces on the tubes is initiated. If the throw of the plunger 26 in the herein illustrated embodiment or the thickness of the work pieces is such that engagement of the latter with the marking edges 90 does not occur until the plunger is at the end of its downward stroke, upon rise of the plunger any downward pressure exerted by the stripper plate posts 107 and 108 on the outer portions of the levers 104 will be released and the marking die formed by the plate 88 and the strips 89 will fall by gravity to its normal retracted position, and only the marking die, with the attached posts 94 and the bars 109, will exert any downward pressure on the levers 104. If, however, the throw of the plunger 26 in the herein illustrated embodiment or the thickness of the work pieces is such that when engagement of the latter with the marking edges 90 occurs the plunger has not yet reached the end of its downward stroke, it is obvious that the plunger, acting through the stripper plate 73 and its posts 107 and 108, subjects to downward pressure not only the outer portions of the levers 104 but also the elevated marking die itself and the upwardly swung inner portions of the levers. As some part of the die structure would undoubtedly break or give way under these conditions if the connections between the plate 88 and the levers comprised a solid, unyielding construction, accommodation to prevent breakage is provided by making the levers

themselves of resilient spring material. Since the inner ends of the levers are spaced above the tube plate 68 when the inner portions of the levers are swung upwardly, it will be seen that space is provided for the downward flexing of the inner portions of the levers toward the tube plate, which flexing makes possible the descent of the marking die under the influence of the plunger. The marking die of the herein illustrated embodiment is thus during movement both upwardly and downwardly mounted upon supports, i. e., the levers 104, that are resilient and yielding.

Upon elevation of the plunger 26, the stripper plate 73 is released and this is accompanied by the stripping action of the work pieces from the tubes 67 and the eventual resumption of the marking die to its normal retracted position. But in those situations in which the marking die is pressed downwardly against the yielding resistance of the downwardly flexed inner portions of the levers 104 as the plunger 26 descends, it will be seen that as long as such downward flexing continues during upward movement of the plunger, so long will the inner portions of the levers exert upward pressure on the marking die. In view of this operation, it will be seen that the downwardly flexed inner portions of the levers, acting through the marking die, cause the marking die to exert stripping pressure upon the work as the plunger rises, and this stripping pressure, being exerted within the opening 83 in the stripper plate 73 and between and adjacent the tubes 67, provides that stripping pressure will be exerted against portions of the work pieces which the stripper plate does not contact. As a consequence, the illustrated embodiment of the present invention provides that stripping pressure will be exerted against work piece portions within the area bounded by the opening 83 as well as against portions located outside that area. This stripping pressure within the area of the opening 83 is not exerted independently of the stripper plate 73 but is controlled thereby since it is the posts 107 and 108 depending from the stripper plate which swing the levers 104 to elevate the marking die into engagement with the work and hold it so engaged when the marking die thereafter descends and flexes the inner portions of the levers during further descent of the plunger. The stripping pressure exerted by the flexed levers against the marking die is preferably less than that exerted by the springs 77 against the stripper plate, and this is achieved by making the levers of spring material which, in the operation of the die structure, offers less resistance to flexing than do the springs 77 to compression. With further reference to the action of the levers 104, it will be appreciated that since these levers are not attached to the marking die, the engagement of the inner portions of the levers with the plate 88 is always a slipping or wiping one so that these inner lever portions engage successively different areas of the under surface of the plate 88 both when it is rising and as it descends, and regardless of whether stripping pressure is being exerted by the levers or not. By reason of this wiping contact with the plate 88, the vertical guiding action of the passages 95 for the posts 94 is not interfered with as might be the case were no wiping or sliding arrangement provided, and as a consequence there is no tendency for the marking die to move laterally in engagement with the work and hence no danger of the

marked lines being blurred or thick as the result of such movement.

In view of the above description of both structural and operative features of the illustrated embodiment of the present invention, it is believed that little need be added by way of summary of the operation of the embodiment as a whole. Once the cords 177 and 191 are attached to the die structure, the latter will assume its normal or operative position in the machine—on the table 36 in the illustrated embodiment. But since the pedal mechanism functions to pull the die structure forward into abutment with the stop plates 116 and since the weight 194 functions to pull the die structure back onto the table, it will be seen that a safety measure is produced in that there is no occasion for an operator to place his hands under the platen 28. In fact, the only occasion for an operator even to reach toward the press machine when the apparatus is set up for use is to grasp the handle 148 to pull the roll carriage forward, and he need not push it back since the springs 162 take care of that automatically when the handle 148 is released. There is no danger of the table 36 and the guideway formed by the plates 48 and 49 tipping forward under the weight of the die structure when it is pulled forwardly on the rails 61 and 62, as the bolts 44 received by the openings 45 in the rear wall of the table 36 prevent such a result.

It will be appreciated that instead of having the front faces of the plates 152 and 153 form stops to limit the rearward movement of the roll carriage, this result could be achieved by having the slide blocks 119 abut the rear closed ends of the guideway slots 63 and 64. The disclosed stop arrangement is to be preferred, however, since strain on the apparatus inherent in the use of stops is thereby better distributed. No stops corresponding to the plates 152 and 153 are herein provided for limiting the forward movement of the roll carriage as such stops have been found to be unnecessary. Marking dies do not usually extend forwardly of the die blocks or bases of die structures, and as the stop plates 116 are located well rearwardly of the front ends of the slots 63 and 64, an operator can easily tell by view how far forward the roll carriage need be pulled to insure that marking substance is applied to the foremost marking edges. Should situations arise where forward stops are desirable, however, the slots 63 and 64 may be made sufficiently short to insure that the slide blocks 119 will abut their forward ends, or preferably the outer faces of the guideway plates 48 and 49 may be provided with stop members aligned with the plates 121 and 122. It will also be appreciated, as more fully set forth above, that it is entirely within the scope of the present invention to use cutout, edging, or pinking dies in the place of or in association with the tubes 67 in the herein illustrated, self-contained die structure, and it is obvious that the pedal and weight mechanism herein disclosed may be used where a given die structure embodies only marking or only cutting dies.

In addition to the improvements noted above which the present die structure makes over that disclosed in my said copending application, certain other improvements are herein involved. The structure of my said copending application embodies the use of stationary cams for elevating the marking die through contact with elements corresponding to the bars 109 of the present invention. But as the cams are stationary

the marking edges remain elevated after the roll carriage has been retracted, and as a consequence it is necessary for an operator to push the die structure off the cams before work pieces can be mounted on the stripper plate, and then to give the die structure a second push to place it on the table. The present invention, by providing in the illustrated embodiment for movable cams which are operatively connected to and controlled by the roll carriage, which is operatively connected to the levers 159, insures not only that the marking die will drop upon retraction of the roll carriage, thereby rendering it unnecessary to move the die structure part way rearward in order to mount work upon it, but also that only one movement of the die structure is necessary to transfer it to its operative position in the machine from the point where the marking edges receive marking substance, thereby making for speedier use. The present invention, by not requiring that an operator pull a die structure forward in order to pull a roll carriage forward, and by not requiring that an operator reach over or around a partially advanced roll carriage in order to remove cut and marked work pieces from the stripper plate, as are modes of operation of the particular structure disclosed in my said copending application, thus requires much less physical exertion on the part of the operator and hence minimizes fatigue. It will be noted further that with the die structure in its outer position, the finished work can be removed and new work can be placed on the stripper plate and gauged, without obstruction of the said plate by projecting marking edges. This supplies a single station for all work handling operations. In the former patent of applicant the work must be withdrawn from the stripper plate after decoration before the die assembly passes over the stationary cams which elevate the marking die, and projects the marking edges to a position of pushing the work off of the stripper, thus smearing the work or at least making withdrawal of the work without smearing it a delicate operation. In like manner the die assembly must be moved away from inking position before new work is mounted on the stripper plate. By using a movable cam for the marker, and coupling up the ink roll carriage with that cam for conjoint operation, the above shortcoming of the embodiment illustrated in the patented structure is avoided.

Nothing herein explained is to be interpreted as limiting the present invention in the scope of its application to use in connection with the particular structure or the particular mode of operation or both which have been selected herein for purposes of explanation and illustration. The particulars of construction herein set forth are well suited to one mechanical embodiment of the present invention, but the invention is not limited to these particulars nor to the conjoint use of all the disclosed features, and it is to be understood that the particulars herein illustrated are not essential since they may be variously modified within the skill of the artisan without in any way departing from the true scope of the actual invention, characterizing features of which are set forth in the following claims which contain generic terms and expressions that are inclusive of various modifications.

What is claimed as new is:

1. In a marking and cutting die structure, the combination with a support, a stripper plate mounted for movement toward and away from the support, marking and cutting dies mounted

on the support, each die having a base portion and the marking edges of the marking die being normally in a retracted position with respect to the plane of the cutting edges of the cutting die, of means, forming part of the die structure and including flat springs having portions interposed between the two die base portions and engageable with the marking die base portion, actuatable by the stripper plate during its movement toward the support to move the marking die so that its marking edges approach the plane of the cutting edges.

2. In a marking and cutting die structure, the combination with a support, a work-engaging stripper plate mounted for movement toward and away from the support, marking and cutting dies mounted on the support, and means actuatable to cause the stripper plate to exert work-stripping pressure, of means, controlled by the stripper plate and including resilient members wipingly engageable with the marking die and extending laterally from positions spaced from the dies into interposition between them, actuatable to cause the marking die also to exert work-stripping pressure.

3. In an ornamenting machine, the combination with a die structure adapted to be supported in the machine and provided with a cutting die and a marking die, a support in the machine for receiving the die structure for its positioning operatively in the machine and for supporting the die structure prior to its operative positioning in the machine, means actuatable while the die structure is supported prior to its said operative positioning in the machine to cause relative movement between the dies so that the marking edges of the marking die are in a location to receive marking substance to the exclusion of the cutting die, and means for depositing marking substance on the marking edges while they are in said location, of means controlled by the depositing means for actuating the actuatable means to effect said marking edges location.

4. In an ornamenting machine, the combination with a die structure adapted to be supported in the machine and provided with a cutting die and a marking die, a support in the machine for receiving the die structure for its positioning operatively in the machine and for supporting the die structure prior to its operative positioning in the machine, normally deactuated means actuatable while the die structure is supported prior to its said operative positioning in the machine to cause relative movement between the dies so that the marking edges of the marking die are in a location to receive marking substance to the exclusion of the cutting die, means for depositing marking substance on the marking edges while they are in said location, and means controlled by the depositing means for actuating the actuatable means to effect said marking edges location, of means operatively connected to the depositing means for returning the actuatable means to its normally deactuated condition upon the completion of marking substance deposition.

5. In an ornamenting machine, the combination with a die structure adapted to be supported in the machine and provided with a cutting die and a marking die, a support in the machine for receiving the die structure for its positioning operatively in the machine and for supporting the die structure prior to its operative positioning in the machine, means located at a level above the die structure as it is supported prior to its said operative positioning in the machine and adapted

for the deposition of marking substance on the marking edges of the marking die, means actuatable to elevate the marking die so that its marking edges are above the cutting die and in a location to receive marking substance to the exclusion of the cutting die, said depositing means being movable to effect marking substance deposition, of means operatively connecting the elevating means and the depositing means to actuate the former during movement of the latter.

6. In an ornamenting machine, the combination with a die structure adapted to be supported in the machine and provided with a cutting die and a marking die, a support in the machine for receiving the die structure for its positioning operatively in the machine and for supporting the die structure prior to its operative positioning in the machine, means located at a level above the die structure as it is supported prior to its said operative positioning in the machine and adapted for the deposition of marking substance on the marking edges of the marking die, means actuatable to elevate the marking die so that its marking edges are above the cutting die and in a location to receive marking substance to the exclusion of the cutting die, said depositing means being movable from and to one position to and from a different position to effect marking substance deposition, and means operatively connecting the elevating means and the depositing means to actuate the former during movement of the latter to said different position, of power means for deactuating the former during movement of the latter to said one position.

7. In a combined marking and cutting die structure, the combination with a support and marking and cutting dies mounted thereon, each die having a base portion and the marking edges of the marking die being normally in a retracted plane with respect to the plane of the cutting edges of the cutting die, of means, forming part of the die structure and including flat springs having portions interposed between the two die base portions, actuatable to cause relative movement between the dies to decrease the spacing between the two planes.

8. In a combined marking and cutting die structure, the combination with a support and marking and cutting dies mounted thereon, each die having a base portion and the marking edges of the marking die being normally in a retracted position with respect to the plane of the cutting edges of the perforating die, of means, forming part of the die structure and including flat springs having portions interposed between the two die base portions, actuatable to move the marking die so that its marking edges approach the plane of the cutting edges.

9. In a combined marking and cutting die structure, the combination with a support, a cutting die having a base portion and mounted on the support in stationary relation with respect thereto, and a marking die having a base portion and movable away from and back toward the cutting die base portion and normally resting thereon, of means, forming part of the die structure and including flat springs portions of which are interposed between the two die base portions and engageable with the marking die, actuatable to move it off the cutting die base portion and to form a yielding support for the marking die when it is not resting on the cutting die base portion.

10. In an ornamenting machine, the combination with a support, a die structure adapted to

be supported on the support and provided with a cutting die and a marking die, a guideway for receiving the die structure for positioning on the support and for supporting the die structure preliminary to its positioning on the support, normally de-actuated means actuatable while the die structure is supported by the guideway preliminary to said positioning to cause relative movement between the dies so that the marking edges of the marking die are in a location to receive marking substance to the exclusion of the cutting die, means for depositing marking substance on the marking edges while they are in said location, and means controlled by the depositing means for actuating the actuatable means to effect said marking edges location, of power means for throwing the depositing means out of operation.

11. In an ornamenting machine the combination of a die supporting slide, and a die structure 20 slidable thereon from a work receiving and removing station to an operating station, said die structure comprising a cutting die, and a work supporting stripper plate supported resiliently with relation thereto, and a marking die having marking edges, said marking die supported movable with reference to the cutting die and strip-

per, and beneath the stripper, said stripper having an orifice therein through which the marking edges of the marking die may protrude, an inking element movable to and from the die structure at the work receiving station and means operable at the work receiving station for moving the marking die so that its edges project through the stripper, and simultaneously moving the inking element to contact said marking edges, and then returning both to inoperative position, including means for holding the marking die normally in a position retracted from the stripper.

12. The combination of claim 11, in which the 15 inking element is supported to be movable from a normally retracted position unobstructing the work receiving station of the die structure and above the path of the die structure to a position of engaging the said marking edges.

13. The combination of claim 11 in which the 20 means operable at the work receiving station comprises operator controlled means connected to the inking element, and means connected for operation through the movement of the inking 25 element and applied to the marking die.

CHARLES E. NEWTON.
